UNITED STATES PATENT OFFICE.

JOHN W. SWEENEY, OF SUGARLAND, TEXAS.

WATER-CRAFT PROPELLER AND VENTILATOR.

Application filed January 21, 1926. Serial No. 82,702.

This invention relates to new and useful improvements in a motor craft propeller and ventilator.

One object of the invention is to provide a device of the character described specially designed for use on water craft for ventilating and assisting in propelling the same.

With the above and other objects in view this invention has particular relation to certain novel features of construction, operation and arrangement of parts, an example of which is given in this specification and illustrated in the accompanying drawings, wherein:—

15 Figure 1 shows a fragmentary plan view of the device, partly in section, and

Figure 2 shows a side view thereof.

Referring now more particularly to the drawings, wherein, like numerals of reference designate similar parts in each of the figures the numeral 1 designates a floor or deck of a boat, or other water craft, and the numeral 2 designates a motor mounted thereon. A drive pulley 3 is fixed on the motor 25 shaft 4 in alignment with the pulley 5, which is loosely mounted on the line shaft 6. Splined on the shaft 6 there is a cone clutch member 7 which is operable into and out of frictional engagement with the pulley 5 in the usual manner, through the shift lever 8. The shaft 6 may thus be 30 operatively connected with or disengaged from the motor 2.

The numeral 9 designates a suction tube, 35 adapted to be connected with the cabins, or compartments of the vessel to be ventilated and the rear end 10, of this tube is downwardly turned and its discharge end 11, is rearwardly turned and submerged in the 40 water.

Incorporated in this tube there is a suction fan 12 whose shaft has a belt pulley fixed thereon.

The numeral 14 designates a counter shaft 45 which has a pulley 15 fixed thereon aligned with the pulley 13. The counter shaft also has a pulley 16 fixed thereon aligned with the pulley 17 which is fixed on the line shaft 6. The belts 18, 19, and 20 transmit rotation from the motor to the line shaft, from the line shaft to the counter shaft, and from the counter shaft to the fan pulley, respectively.

The fan 12 creates suction through the 55 tube 9 and sucks the impure air from the compartments with which it is connected.

Incorporated in this tube there is a casing 21, which has vertically aligned bearings in which there is a vertical fan shaft 22. Enclosed within the casing 21 and fixed on said shaft there is the turbine 23 disposed so that the current passing through the tube 9 will rotate it and the shaft 22, as well. Fixed onto the lower end of the shaft 22 is the conventional overhead fan, having the 60 inclined vanes 24, which serve to keep the compartment, in which the fan is located, cool. The tube 9 has a by-pass 25 around the casing 21 and there is a gate valve 26 adapted to control the passage of air 65 through the casing 21. By closing said valve the air current may be diverted through the by pass 25 and the fan 24 thus stopped. It is to be noted that the tube 9 may have a sufficient number of branches 70 to make provision for ventilating any or all of the compartments of the vessel, as well as for driving any number of fans, as 75 desired.

One end of the line shaft 6 has the spaced 80 friction discs 27, 27, fixed thereon whose facing sides are cone shaped and between them there is the driving cone 28 which is fixed on the adjacent end of the shaft 29. This shaft is mounted to rotate in the bearings 30, 31, the latter of which is located adjacent the cone 28 and is eccentrically mounted in the ring 32. This bearing 31 may be rotated through the hand lever 33 so as to shift the cone 28 into frictional engagement with either of the discs 27, 27, and thus reverse the rotation of the shaft 29.

There is a propeller shaft 34 disposed parallel with the shaft 29 and fixed on it there is a pulley 35 aligned with the pulley 36 fixed on the shaft 29. A belt 37 operates over these pulleys and transmits rotation from the latter to the former. The shaft 34 has the propellers 38, 38, fixed thereon and the counter shaft 14 has the 90 propellers 39, 39, fixed thereon.

These propellers assist in propelling the vessel along, particularly in the case of small craft. The discharge of air from the submerged discharge end of the tube 9 also 105 assists somewhat in propelling the vessel.

What I claim is:

1. A device of the character described including a ventilating tube, a current generator associated with the tube, a motor for 110 driving said generator to create a current through said tube, a turbine associated with

said tube and adapted to be driven by said current, a fan operatively connected with and adapted to be driven by said turbine.

2. A device of the character described including a ventilating tube, a current generator associated with the tube and adapted to create a current therethrough, a turbine associated with said tube and adapted to be rotated by the current passing therethrough, a fan adapted to be driven by the turbine, said tube having a by-pass around the turbine, a valve adapted to control the flow of current through said tube and by pass, a motor for driving said generator.
- 10 3. A device of the character described including a ventilating tube, a current generator associated therewith and adapted to create an air current therethrough, a turbine associated with the tube, a valve controlling the application of said current to the turbine, a by-pass carried by the tube around said turbine and valve, a fan operatively connected with and adapted to be driven by the turbine.
- 15 4. A device of the character described in-

cluding a ventilating tube, a current generator associated with the tube, a motor for driving said generator, to create a current through said tube, a turbine associated with said tube and adapted to be driven by said current, a fan operatively connected with and adapted to be driven by said turbine, and propellers operatively connected with and adapted to be driven by said motor.

5. A device of the character described including a ventilating tube, a current generator associated with the tube, a motor for driving said generator, to create a current through said tube, a turbine associated with said tube and adapted to be driven by said current, a fan operatively connected with and adapted to be driven by said turbine, a propeller operatively connected with and adapted to be driven by said motor and means for reversing the direction of rotation of said propeller.

In testimony whereof I have signed my name to this specification.

JOHN W. SWEENEY.
